UNITED STATES PATENT OFFICE

CHARLES B. LOWE, OF DETROIT, MICHIGAN, ASSIGNOR TO FERRO STAMPING & MANUFACTURING COMPANY, OF DETROIT, MICHIGAN, A CORPORATION OF MICHIGAN

AUTOMOBILE DOOR HANDLE

Application filed August 16, 1928, Serial No. 300,931. Renewed January 23, 1933.

This invention relates to door handles, and the like, and more particularly to handles designed for use on the doors of automobiles and other vehicles.

The principal object of my invention is the provision of a door handle that in its unlocked position will operate to move the lock bolt into and out of operative relation to the striker plate carried by the door jamb in the usual manner of door locks, but which, when in locked position, will be freely rotatable without influencing the movement of such lock bolt.

Another object of this invention is the arrangement of a door handle so that it is freely rotatable upon a portion of the lock shaft and in the usual escutcheon plate with key-controlled means for connecting the handle to the lock shaft whenever desired.

20 A further object of this invention is the provision of connecting means between the lock shaft and a freely rotatable door handle comprising a connecting member rotatable with the door handle but slidable longitudinally thereof into and out of driving connection with the lock shaft.

25 A further object of this invention is the arrangement of a tapered cross slot in the lock shaft with its median line offset with relation to the axis of the shaft and a correspondingly tapered offset lug on a slidable member rotatable with the door handle whereby the lug can enter the cross slot of the shaft only when the handle has been 30 rotated to a predetermined position.

35 Other objects and advantages will be apparent from the following description, wherein reference is made to the accompanying drawings illustrating a preferred embodiment of my invention and wherein similar reference numerals designate similar parts throughout the several views.

In the drawings:

Figure 1 is a longitudinal cross-section through a door handle and adjacent portions of a lock shaft, the handle being disconnected from the shaft.

40 Figure 2 is a longitudinal cross-section through the door handle and adjacent portions of the lock shaft, the section being taken

at substantially right angles to the section line of Figure 1.

Figure 3 is a detail cross-section taken substantially on the line 3—3 of Figure 1.

Figure 4 is a detail cross-section taken substantially on the line 4—4 of Figure 2.

Figure 5 is a longitudinal cross-section similar to Figure 1, but showing the lock shaft connected for rotation by the door handle.

Figure 6 is a plan view of the door handle and adjacent portions of the lock shaft in assembled position, and

Figure 7 is a diagrammatic perspective view of the means for connecting the lock shaft and operating handle shown in disassembled positions.

Referring now to the drawings, the number 5 designates a portion of a vehicle door having a metallic cover plate 6 apertured as 70 at 7 for the reception of the operating handle. A lock shaft 8 extends through the door and is fastened at its inner extremity in any desired manner to means for moving the usual lock bolt or the like. It is to be understood that any desired form of lock may be utilized with my improved door handle. The outer extremity of the door handle 8 is formed with a cylindrical portion 9 in the face of which is formed a slot 10 for the reception of a lug 80 11 carried by a connecting member 12. As herein shown, I preferably arrange the slot 10 with its median line offset from the longitudinal axis of the shaft 8, and also incline at least one of its side walls to make the slot 85 a tapered one. The lug 11 is correspondingly shaped, and formed with length and thickness of rear portion slightly greater than the depth and thickness of the front portion of the slot 10, whereby the lug 11 upon entering the slot 10 will always snugly engage against the side walls of the slot, even though long usage slightly widens the slot because of wear.

The rounded outer extremity 9 of the shaft 90 8 fits within and forms a bearing for the inner extremity of an elongated hollow cylinder 13, the rear portion of which is turned substantially as shown to form a stop for the rounded extremity of the shaft during assem-

60

bly, while the outer extremity of the cylinder 13 is formed with radial lugs 14 for securing the cylinder to the knob or lever portion 15 of the door handle. This lever portion 15 of the door handle may be of any suitable construction, and only so much thereof as is needed to show the positioning of the cylinder 13 and its associated parts is illustrated herein. Within the outer portion 10 of the cylinder 13 is adapted to be mounted a key-controlled tumbler lock 16, the rotatable portion 16^a of which carries a pin 17 adapted to extend within a cam slot 18 in the connecting member 12, and the rotatable portion 16^a is of lesser diameter than the barrel 16 of the tumbler lock to provide a support for the connecting member and space for the radial extension of the pin 17 between the periphery of the rotating portion 16^a of the lock and 20 wall of the cylinder 13. Between the shoulder formed by the larger barrel portion 16 of the lock and the outer extremity of the connecting member 12 is arranged a coiled spring 19 to normally force the connecting member 12 toward the inner extremity of the cylinder 13 and into engagement with the slotted rounded extremity 9 of the lock shaft 8. The connecting member 12 is best shown 30 in Figure 7, and comprises a hollow cylindrical forward portion in the wall of which is formed the cam slot 18 and a solid rear portion terminating in the tapered lug 11 and provided with an aperture for the reception of a radially extending pin 20. The 35 hollow cylindrical portion of the connecting member 12 loosely fits over the reduced portion 16^a of the tumbler lock 16, substantially as shown in Figures 1 and 5, with the pin 17 extending through aligned slots 21 in the 40 wall of the cylinder 13 (note Figure 2). The slots 21 are preferably arranged longitudinally of the cylinder 13 and the pin 20 is guided by the walls of the slots 21 during the sliding movements of the connecting member 12 45 while serving to prevent rotation of the connecting member except with the cylinder 13 and attached portions of the door handle.

An escutcheon 23, preferably of ornate appearance, is secured upon the door 5, as by 50 screws 24, and is provided with a central portion extending outwardly from the door a sufficient distance to permit the insertion of the pin 20 through the slots 21 and aperture in the connecting member 12 after the escutcheon has been placed over the inner extremity of the cylinder 13 (note Figure 2). A 55 spacer sleeve 22, also preferably of ornate appearance, is arranged to surround the cylinder 13 between the lever portion 15 of the handle and the escutcheon 23, the contacting portions of the spacer sleeve and escutcheon being shaped to provide ready rotation of the sleeve on the escutcheon.

In assembling my improved door handle, 60 the cylinder 13 and spacer sleeve 22 are se-

cured to the lever portion 15 of the door handle in any desired manner, after which the lock shaft 8 is introduced into the cylinder 13 through an aperture in the lever portion 15 of the handle and permitted to pass through the cylinder until the rounded portion 9 of the shaft engages the inturned rear extremity of the cylinder. The shaft is then secured in such position by any suitable means, as for example, a split washer 25 extending into a circular slot 26 formed in the shaft directly beyond the rear extremity of the cylinder 13 (note Figures 1 and 2). The spring 19 and connecting member 12 (except for its pin 20) are slid over the reduced portion 16^a of the tumbler lock 16 and the pin 17 inserted through the cam slot 18 of the connecting member into the aperture 17^a therefor in the reduced portion of the lock (note Figure 7). The tumbler lock 16 and associated parts are then inserted into the forward extremity of the cylinder 13 and firmly fixed therein in any suitable manner so that the tumbler lock will rotate with the cylinder 13. The escutcheon 23 is then brought over the rear extremity of the cylinder 13 until it engages the rear extremity of the spacer sleeve 22, after which the pin 20 is inserted through the connecting member 12 so that its extremities engage the walls of the aligned slots 21 in the cylinder 13. A light spring 27 is then passed over the rear extremity of the cylinder 13 into engagement with the escutcheon 23 and secured in place by a lock washer 28 or other suitable means. The lock washer 28 is shaped so that it can move over the cylinder 13 in one direction, but cannot move in the reverse direction and serves to bind all of the connected parts against accidental dislocation. The cylinder 13 extends rearwardly, however, beyond the lock washer 28 and the escutcheon 23 so that it and the lock shaft 8 will pass through the aperture 7 in the door when the door handle is secured upon the door (note Figures 1 and 2). The door handle assembly so far described is shown in Figure 6, and can be packed and shipped in any suitable manner.

When it is desired to secure the door handle upon vehicle door it is only necessary to insert the lock shaft 8 and rear extremity of the cylinder 13 through the aperture 7 in the door and then secure the lock shaft within the control element for the movement of the lock bolt. Such insertion within the aperture 7 of the door brings the escutcheon 23 into engagement with the outer face of the metallic cover plate 6, and it is fixed in such position by the screws 24. The door handle and associated parts are now firmly secured upon the door so that the handle can rotate but cannot be removed longitudinally to extricate it from the door until the lock shaft 8 is freed from engagement with the control element of the door lock. Re-

removal of the screws 24 from the escutcheon plate will not suffice to permit withdrawal of the door handle from the door lock, and the positioning of the inner extremity of the cylinder 13 and shaft 8 within the aperture 7 of the door places it beyond the reach of a malicious or mischievous person even though the escutcheon be completely removed.

In use, the connecting member 12 is slid 10 into and out of engagement with the lock shaft 8 by rotating the key-controlled tumbler lock 16 as desired. When in its unlocked position, as shown in Figure 5, the driving lug 11 of the connecting member is 15 pressed by the coiled spring 19 into the cross slot 10 in the rounded portion 9 of the lock shaft. In such position, rotation of the lever portion 15 of the door handle to open or close the door will simultaneously rotate the lock shaft 8, and through it move the lock bolt as desired. In its locked position, as shown in Figures 1 and 2, the lug 11 of the connecting member 12 is completely withdrawn from the cross slot 10 of the lock shaft, and 20 in such position the door handle is freely rotatable without serving to move the lock shaft 8, the cylinder 13 and associated parts rotating on the rounded portion 9 of the lock shaft and within the escutcheon 23. The 25 movement of the connecting member from its unlocked position, as shown in Figure 5, to its withdrawn or locked position as shown in Figures 1 and 2, is accomplished by partially rotating the key-controlled tumbler lock 16 relatively to the cylinder 13. This rotary movement of the tumbler lock 16 30 serves to swing the pin 17 fixed in the reduced portion 16^a of the tumbler lock, and since the inclined rear wall of the cam slot 18 of the connecting member is maintained in contact with the pin 17 through the pressure exerted by the coil spring 19, such movement of the pin 17 will serve to slide the connecting member 12 along the reduced portion 17^a of the tumbler lock. To again connect the door handle with the lock shaft it is 35 only necessary to rotate the tumbler lock 16 in the reverse direction, thereby moving the pin 17 into the wider portion of the slot 18, and permitting the spring 19 to slide the connecting member 12 toward the lock shaft. Since, however, the door handle may have 40 been rotated to any angle while disconnected from the lock shaft, it is possible that the 45 mere releasing of the connecting member 12 by so rotating the tumbler lock will not suffice to permit the lug 11 of the connecting member to enter the slot 10 in the lock shaft. If the lug and slot are not in correct alignment the rear face of the lug 11 will engage 50 the front face of the rounded portion 9 of the lock shaft, and it will be necessary to rotate the handle until the lug 11 aligns 55 with the slot 10, whereupon it snaps into the slot 10 because of the pressure exerted on the 60 connecting member by the coil spring 19. The desired rotation of the tumbler lock 16 through the instrumentality of its key is not interfered with, however, regardless of the angle in which the handle may stand when the lock is rotated, the widened portion of the cam slot 18 permitting the pin 17 to rotate while the connecting member 12 is held from further sliding movement because of the engagement of the lug 11 with the face of the 65 rounded portion 9 of the shaft. It will be noted that if the slot 10 were arranged with its median line co-incident with the axis of the shaft 8, the lug 11 could snap therein at two positions in the rotation of the door handle, these positions being separated from each other by 180°. Since, however, it is usual to form the lever portion 15 of a vehicle door handle with a comparatively long arm and a comparatively short arm, this would 70 result in the connecting of the handle with the door shaft with the long arm facing either the front or rear of the car and the door handles on adjacent doors of the car might not always have their long arms extending in the same direction. To insure the entrance of the lug 11 into the slot 10 of the lock shaft 8 only when the long arms of the door handles are extending in the desired direction, I have offset the cross slot 10 and lug 11 with relation to the longitudinal axis of the lock shaft and door handle, enabling the entrance of the lug into the slot only in 75 one position during the rotation of the door handle.

From Figure 2 it will be noted that the lug 11 is snugly fitted within the slot 10 while the pin 17 is clear of the rear wall of the wider portion of the cam slot 18. Accordingly, it is possible for the lug 11 to further enter the slot 11 after long usage has effected wear upon the snugly engaging tapered sides of the slot and lug respectively, thus preventing a loose fit of the lug within the slot with consequent rattling during vibrations of the vehicle.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

What I claim is:

1. In combination with a door lock, a lock shaft secured adjacent one extremity to the movable portion of the door lock, a rotatable door handle including an elongated hollow cylinder, a rotatable lock barrel mounted partially within the cylinder, a connecting member movable within the cylinder into and out of engagement with the free extremity of the lock shaft, the adjacent extremities of the connecting member and lock shaft being pro-

vided one with a lug and the other with a recess adapted to interfit, the connecting member being also formed with a cam slot having circumferentially spaced wide and narrow portions, a pin extending from the lock barrel into the cam slot, and a spring arranged within the cylinder to press the connecting member toward the lock shaft whenever the pin is in a wide portion of the cam slot where 5
10 by variations in the extent of entrance of the interfitting lug and slot may be secured.

2. In combination with a door lock, a lock shaft secured adjacent one extremity to the movable portion of the door lock, a rotatable door handle including an elongated hollow cylinder, a rotatable lock barrel mounted partially within the cylinder, a connecting member movable within the cylinder into and out 15
20 of engagement with the free extremity of the

lock shaft, the adjacent extremities of the connecting member and lock shaft being provided one with a lug and the other with a recess adapted to interfit, the connecting member being also formed with a cam slot 70 having wide and narrow portions, a pin extending from the lock barrel into the cam slot, and a spring arranged within the cylinder to press the connecting member toward the lock shaft whenever the pin is in a wide 75 portion of the cam slot whereby variations in the extent of entrance of the interfitting lug and slot may be secured, said interfitting lug and slot being provided with spaced straight and tapered side walls to permit engagement 80 of the side walls of the interfitting members ahead of engagement of the end faces thereof.
